(57) **CLAIM**

The ornamental design for the flexible package with integral tab, as shown and described.

DESCRIPTION

FIG. 1 is a perspective view of the flexible package with integral tab according to our new design;

FIG. 2 is a back elevational view thereof;

FIG. 3 is a front elevational view thereof;

FIG. 4 is a bottom view, the other end being a mirror image thereof;

FIG. 5 is a side elevation view thereof;

FIG. 6 is a perspective view of the flexible package with integral tab in a partially open position; and,

FIG. 7 is perspective view of a flexible package with integral tab in a partially open position, according to the first embodiment.

In the drawings, the dashed lines represent a tearable line of weakness in the flexible package with integral tab and form a part of the claimed design. The smaller broken lines are for the purpose of illustrating environment only and form no part of the claimed design.
